THREAD TENSIONING DEVICE

Horace H. Burdett, Milford, Mass., assignor to
 Draper Corporation, Hopedale, Mass., a corpora-
 tion of Maine

Application May 13, 1940, Serial No. 334,804

6 Claims. (Cl. 139—217)

This invention pertains to automatically threading loom shuttles and has more particular reference to such shuttles having automatically threading tension devices for applying tension to the running filling thread.

Shuttles of the type mentioned are used in bobbin changing looms wherever the character of filling thread employed or cloth being woven is such as to require more tension on the filling thread than is obtainable with shuttles having simple threading blocks. Of the various types of tension devices heretofore proposed, the spring clamp type, so-called, is to be preferred from the standpoint of simplicity and ruggedness of design and also because of the more uniform tension which it provides.

However, such prior spring clamp tension devices have been unsatisfactory in that they failed to provide a sufficiently uniform tension and sufficiently fine adjustment of the tension.

The principal object of the present invention is to provide, in an automatically threading tension device of the spring clamp type, means whereby a more uniform tension is produced and finer adjustment of the tension is readily obtainable.

Other objects and advantages of the invention will be made manifest in the following more detailed description of the preferred embodiment of the invention and by reference to the accompanying drawing, wherein:

Fig. 1 is a plan view of the thread delivery end of the shuttle;

Fig. 2 is a view in section as indicated by line 35 2—2 of Fig. 3; and

Fig. 3 is a view in cross-section taken on line 3—3 of Fig. 2.

The shuttle shown on the drawing is comprised of a shuttle body 1 having a cavity 2 for receiving an automatically replaceable filling carrier such as bobbin 3, a threading block 4, and a side delivery eye 5. The shuttle body may be provided with a thread trapping wall 6 as more fully disclosed in patent to W. I. Stimpson, No. 1,985,960, granted Jan. 1, 1935.

The shuttle has a longitudinally extending thread passage 7 which is in alignment with the cavity 2. The thread passage or as much thereof as is in the threading block 4 is defined by the front wall 8 and the rear wall 9 of the threading block.

A guard or horn 10 projects from the front wall 8 outwardly and rearwardly, as in the said Stimpson patent. The term "outwardly" is herein used 55 to mean in a direction from the cavity 2, longi-

tudinally of the shuttle toward the tip, i. e. toward the right on Figs. 1 and 2. Other expressions denoting direction are applicable to the shuttle when the same is considered to be positioned in the loom.

The shuttle is provided with a tension device, which device may comprise a pair of friction members yieldingly pressed together for exerting a slip-grip upon the running filling. The tension device as shown is preferably carried by the 10 threading block at the inner end of the thread passage in the latter, there being a front friction member 11 and a rear friction member 12. The members 11 and 12 extend transversely of the filling thread and thread passage, preferably at 15 an angle to the perpendicular axis of the threading block 4 as best shown by Fig. 3.

The particular friction members 11 and 12 shown on the drawing, may be formed from elongated bodies of flat steel bent into the shape 20 best shown by Fig. 3. The upper end of friction member 11 is provided with a horizontally extending guide lug 13 entering into a bushing 14 in a recess 15 in the threading block 4, whereby the friction member is movably guided and supported. The upper end of friction member 12 is provided with a horizontally extending lug 16 entering into a bushing 17 in a recess 18 in the threading block 4, whereby the friction member is movably guided and supported. The friction 25 members 11 and 12 are provided adjacent their bottom ends with aligned holes 19 and 20 respectively for the reception of supporting means. The supporting means shown may comprise an adjustable screw 21 threaded into the rear wall 30 9 and having a pin 22 projecting from its forward end. The pin 22 being received in an opening 23 in the front wall 8, the pin 22 passes through the holes 19 and 20 in the friction members 11 and 12 and supports said friction members. The inner face 24 of the screw 21 abuts the rear friction member 12. By turning said screw the friction members 11 and 12 may be adjusted in their relation to the side walls of the thread slot.

The friction members 11 and 12 may be yieldingly pressed together by suitable spring means. In the construction shown, member 12 is pressed toward member 11 by a spring 25 which engages between member 12 and an adjusting screw 26 threaded into the rear wall 9 of the threading 40 block. Member 11 is pressed toward member 12 by a spring 27 which engages between member 11 and an adjusting screw 28 threaded into the front wall 8 of the threading block.

An important feature of novelty of the shuttle 55

shown resides in the relative location of the spring means such as 25 and 27. As best seen on Fig. 3 these springs are staggered in relation to each other.

5 In the prior types of spring clamp tension devices where the tension means are in horizontal axial alignment, there is a tendency for the friction members to press against the running filling thread with a varying pressure. Starting with 10 slight pressure at the entrance end the pressure increases up to the point of location of the tension means and decreases from that point downward to the bottom of the friction members. Thus the pressure exerted by the friction members 15 is not uniform throughout their length. By vertically spacing the tension means, a more uniform pressure is exerted by the friction members throughout their length. The inner face 24 of screw 21 acts as an abutment about which members 11 and 12 are moved by tension springs 25 and 27. Spring 25 moves the members clockwise about the abutment and spring 27 moves the members counter-clockwise about the abutment (as viewed on Fig. 3). Due to the fact that 20 spring 25 is located further from the abutment 24 than is spring 27, the pressure exerted by members 11 and 12 against each other, and of course against the running filling thread therebetween, will be substantially uniform throughout their 25 lengths.

Also by having the adjusting tension means spaced vertically a finer adjustment of the tension exerted by the friction members can be obtained. Because of their location in relation to 30 the friction members 11 and 12, the front and rear tension springs exert a different pressure against the filling thread. It has been found that one turn of the back adjusting screw 26 is equal to approximately one half turn of the front 35 adjusting screw 28. This is very important in obtaining the fine adjustments necessary for yarns such as rayon of 100 denier and under.

Having thus fully disclosed the preferred embodiment of my invention, I claim:

45 1. An automatically threading loom shuttle having a cavity for a filling carrier, a threading block having a longitudinally extending thread passage in alignment with said cavity, and a tension device in said thread passage, said tension device comprising a pair of opposed friction members extending transversely of said thread passage said members being laterally movable in relation to each other throughout their lengths and yieldingly pressed together for exerting a 50 slip-grip upon the running filling thread, said tension device being open at one end to thereby provide a thread entrance, yielding means pressing against one of said friction members, a second yielding means pressing against the other of said 55 friction members, said second yielding means being spaced longitudinally of said members from said first yielding means, and means for adjusting the tension of said yielding means.

2. The combination in a shuttle having a longitudinal threading slot, of two friction members having contacting friction faces, means located adjacent the top of said slot for movably supporting said members, an adjustable abutment extending transversely of said slot adjacent the 60 lower end thereof, an adjustable tension member located on one side of said friction members and pressing said friction members against said abutment, a second adjustable tension member located on the other side of said friction members 65 and pressing said friction members away from

said abutment, said second named tension member being located substantially twice the distance from said abutment as said first named tension member, whereby said friction members exert a substantially uniform force against each other throughout their length.

3. The combination in a shuttle having a threading block therein, said block having a longitudinal threading slot, of two friction members having contacting friction faces for tensioning the running filling thread therebetween, means located adjacent the top of said slot for slidably supporting said members, an adjustable member extending transversely of said slot adjacent the lower end thereof for supporting said friction members, an abutment carried by said adjustable member against which the lower ends of said friction members rest, a pair of coiled compression springs for pressing said friction members together, one of said springs being located a greater distance above said abutment than the other whereby said friction members are pressed together with substantially a uniform pressure throughout their length.

4. The combination in a shuttle having a longitudinal threading slot, of two friction plates having contacting friction faces, means located adjacent the top of said slot for movably supporting said plates, adjustable means located adjacent the bottom of said slot for supporting said plates and adjusting said plates laterally in relation to the walls of said slot, vertically spaced yielding means intermediate said supporting means for pressing said plates against each other and causing the latter to exert a substantially uniform slip-grip on the running filling, and means for adjusting the tension of said yielding means.

5. An automatically threading loom shuttle having a threading slot therein and also having a pair of oppositely disposed recesses adjacent its upper edge, said recesses opening into said slot, a pair of plates having contacting friction faces for tensioning the running filling therebetween, each of said plates having a guide lug at its upper end projecting into one of said recesses for slidably suspending said plate in said threading slot, an adjustable member extending transversely of said slot adjacent the lower end thereof for supporting said plates, said member having an abutment contacting the lower end of one of said plates whereby said ends may be adjusted in relation to the side walls of said slot, an adjusting screw having resilient means on its forward end for pressing one of said plates against the other, and a second adjusting screw having resilient means on its rearward end for pressing the other of said plates against the plate contacted by said first named resilient means, the points of contact of said resilient means with said plates being located at different distances above said abutment whereby said plates are pressed together with a substantially uniform tension throughout their length.

6. An automatically threading loom shuttle having a cavity for a filling carrier, a threading block having a longitudinally extending thread passage in alignment with said cavity and also having a pair of oppositely disposed recesses adjacent its upper edge opening into said thread passage, and a tension device in said thread passage, said tension device comprising a pair of friction members, each of said friction members having a hole adjacent its bottom end and having a guide lug at its upper end projecting into one of said recesses, a screw threaded into said

threading block adjacent the bottom of said thread passage, said screw having a pin projecting from one end thereof and extending through said openings in said friction members for supporting said members, the inner face of said screw forming an adjustable abutment whereby said friction members are laterally adjustable in relation to the side walls of said thread passage, a compres-

sion spring positioned behind each friction member for yieldingly pressing said members together to exert a slip-grip upon the running filling thread, said springs being spaced vertically from each other, and a pair of adjusting screws 5 threaded into said threading block for adjusting the tension of said springs.

HORACE H. BURDETT.
